EDWARD H. THORNE, OF FALL RIVER, MASSACHUSETTS, ASSIGNOR
TO DOUGLAS MANUFACTURING COMPANY, OF FALL RIVER,
MASSACHUSETTS.

COP-TUBE.

SPECIFICATION forming part of Letters Patent No. 737,531, dated August 25, 1903.

Application filed April 24, 1903. Serial No. 154,124. (No model.)

To all whom it may concern:

Be it known that I, EDWARD H. THORNE, a subject of the King of Great Britain, and a resident of Fall River, in the county of Bristol 5 and State of Massachusetts, have invented a new and Improved Cop-Tube, of which the following is a full, clear, and exact description.

My invention relates to improvements in 10 cop-tubes of that class which are used to contain the winding of yarn in weaving machinery, although the improved tube may be used to good advantage in holding the windings of other material than yarn.

Attempts have been made to produce a 15 cheap cop-tube by making the same of paper; but ordinary tubes, whether made of paper, wood, or other materials, are not satisfactory owing to the tendency of the winding to 20 "sluff" off or become displaced from the tube and to the liability of wooden tubes to break. There is a demand in the trade for a cheap and durable cop-tube which will effectively hold the winding of yarn and other material 25 from "sluffing" off or displacement from the tube; and the object of the present improvement is to produce an improved article which meets the requirements of practical service.

The invention consists of a paper cop-tube 30 having a frictional holding-surface of a peculiar pattern produced thereon by compressing the tube externally to form a series of inclined or conical portions separated by well-defined annular ledges or shoulders, against 35 which the winding is adapted to lodge in a way to wholly overcome slippage along the tube.

Reference is to be had to the accompanying drawings, forming a part of this specification, in which similar characters of reference indicate corresponding parts in all the figures.

Figure 1 is a perspective view, on an enlarged scale, of a paper cop-tube before it is compressed to produce the frictional holding-surface thereon. Fig. 2 is a perspective view of 45 the complete cop-tube. Fig. 3 is a longitudinal section, on a greatly-magnified scale, through a portion of a cop-tube embodying my invention; and Fig. 4 is a cross-section

taken in the plane of the dotted line 4-4 of Fig. 3.

A in Fig. 1 designates a paper cop-tube in an embryo condition, the same being prepared by coiling a strip or sheet of paper upon itself to produce a longitudinal tapered tube of the proper length and of suitable diameter, the 55 coiling of the paper upon itself being represented by the enlarged cross-sectional view in Fig. 4. A cop-tube with a smooth external surface will not meet the requirements of actual service, because of the tendency of the 60 winding to sluff off or become displaced when the article is in use in a weaving-machine, and to overcome this tendency of the winding to sluff I provide the cop-tube with a peculiar form of holding-surface which presents a 65 plurality of concentric ridges or shoulders against which the winding is adapted to lodge.

After the tube shall have been wound in the spiral form from a length of paper, as heretofore described, it is treated by compression to 70 produce the frictional holding-surface shown by Figs. 2 and 3 in the form of a series of tapering or conical sections B and a plurality of concentric annular shoulders or ridges C, each section B tapering from one of the 75 shoulders to the next adjacent shoulder. To produce the frictional holding-surface after the tube shall have been completed, it is placed in a machine, mold, or die of any suitable construction or pattern which exerts 80 sufficient pressure externally on the tube to compress the paper fibers more solidly on certain annular lines than at other points, and thereby produce or form the tapering or conical faces B and the annular ridges or shoulders C. The operation of compressing the tube not only produces the tapering surfaces and the shoulders, but the paper stock or fiber is compressed or condensed more solidly 85 at the smaller ends of the conical surfaces 90 than at the enlarged ends of said surfaces, such condensation of the fibers tending to increase the stiffness and rigidity of the tube, and thereby prolong its durability and life.

In the drawings the conical portions of the 95 tube are shown as inclining toward the smaller

end of said tube; but the shoulders may be arranged for the conical portions to incline in the opposite direction, if desired.

Having thus described my invention, I claim as new and desire to secure by Letters Patent—

1. A paper cop-tube, comprising a spirally-wound paper body having a winding-retaining surface formed by externally compressed, conical faces separated by intermediate shoulders, the fibers of the wound paper body being condensed more solidly at the smaller ends of the conical faces than at the enlarged portions of such faces.

15 2. A cop-tube, comprising a spirally-wound paper body which is externally compressed and is formed with a corrugated winding-retaining surface extending longitudinally of

said body, the fibers of the body being condensed more solidly on certain annular lines 20 than at other points.

3. The method of making cop-tubes, consisting in spirally winding a length or strip of paper upon itself to produce a wound body, and subsequently producing a corrugated 25 winding-retaining surface on the body by condensing the fibers on annular lines and forming a series of well-defined annular shoulders.

In testimony whereof I have signed my 30 name to this specification in the presence of two subscribing witnesses.

EDWARD H. THORNE.
